UNITED STATES PATENT OFFICE.

WILLIAM BOYER, OF VALENTINE, NEBRASKA, ASSIGNOR OF ONE-HALF TO CHARLES H. CORNELL, OF VALENTINE, NEBRASKA.

RAILROAD CROSS-TIE.

No. 895,949.

Specification of Letters Patent. Patented Aug. 11, 1908.

Application filed October 8, 1907. Serial No. 396,378.

To all whom it may concern:

Be it known that I, WILLIAM BOYER, a citizen of the United States, and a resident of Valentine, in the county of Cherry and State 5 of Nebraska, have invented a new and Improved Railroad Cross-Tie, of which the following is a full, clear, and exact description.

This invention relates to cross ties for railroads formed of metal.

When ties of the character indicated are cast into form, it is difficult to render them solid throughout their bodies, and in consequence such ties are liable to break; furthermore, resilience, which is desirable in a metal 15 tie, is very slight in such ties as are formed in one piece by casting or other analogous means.

The object of my invention is to provide a cross tie formed in plate-like sections of steel, 20 that are clamped one upon the other and upon a track rail, thus affording a laminated steel cross tie having great strength, ample resilience and durability, with a minimum weight; and a further object is to provide 25 novel, convenient means for securing track rails and the improved cross ties together, that will permit a necessary endwise movement of the rails for their expansion and contraction due to changes of temperature, and 30 will also permit the quick and easy removal of the multipart cross tie for the track repairs or other purposes.

The invention consists in the novel construction and combination of parts, as is 35 hereinafter described and defined in the appended claims.

Reference is to be had to the accompanying drawings forming a part of this specification, in which similar characters of reference 40 indicate corresponding parts in all the views.

Figure 1 is a longitudinal sectional view substantially on the line 1—1 in Fig. 3, showing one embodiment of my invention; Fig. 2 is a perspective view of the cross tie and rail 45 connection shown in Fig. 1; Fig. 3 is a transverse sectional view of the improved cross tie, substantially on the line 3—3 in Fig. 1, a clamping device being shown by dotted and full lines; Fig. 4 is a transverse sectional 50 view of a track rail, a longitudinal sectional view of a portion of the improved cross tie, and means for securing the track rail on the cross tie, and Fig. 5 is a transverse sectional view of a track rail, and of the rail clamping 55 device slightly modified and partly broken

away, the rail being seated upon a portion of the improved cross tie shown in section.

The improved cross tie, as illustrated in the drawings, comprises a plurality of steel plates 5, 5^a, 5^b, of suitable thickness, having 60 parallel sides and edges, the areas of the plates preferably being reduced successively so that their side edges form steps when they are seated one upon the other, as appears in Figs. 2 and 3.

Three plates are shown to represent the construction of the tie, but it is to be understood that but two plates, or any suitable number greater than two, may be utilized as component members of the laminated cross 70 tie. The improvement is especially well-adapted for the support of T-shaped track rails upon a graded roadbed for a railroad, and is shown as combined with such a rail 6.

In the construction of a railroad of which the laminated cross ties in sufficient number form bases for track rails 6, said ties are as usual arranged transversely on a graded and ballasted roadbed, for the support of said track rails near the ends of the latter and between the same, not shown.

As the cross ties of improved construction are essentially alike, a description of one tie and of the means for connecting a track rail 6 therewith, will suffice for any number of ties 85 and rails employed. The tie sections, composed of the plates 5, 5^a, 5^b, are shown as preferably disposed one upon another, each reduced in width, the plate 5 of the least width being uppermost. It is to be understood, however, that in some cases the plates forming the cross tie, may be reversed in their arrangement, thus disposing the plate of least width lowermost, and the widest plate on top of the others. At a point where 90

the track rail 6 is to be seated and secured upon the composite cross tie, two transversely central slots *a* are formed in all the tie plates, these longitudinal slots being spaced apart a distance which will permit the 100 base of the track rail to be seated on the cross tie between them.

In Figs. 1 and 3, the connection for securing the track rail on the cross tie, and at the same time clamping the plates forming 105 the tie together, is shown in its simplest form and consists of the following details. Two substantially similar gibs 7, 7, are fitted into respective slots *a*, and with their upper jaws 7^a and lower jaws 7^b, closely embracing the 110

base flanges 6^a on the rail 6 and lower tie plate 5^b adjacent to the inner ends of said slots. In the remaining portion of each of the slots *a*, a key 8 is fitted, which tapers 5 edgewise and when forced downward causes the corresponding jaw 7^a to bind upon the base flange 6^a it is seated upon. As shown in Fig. 1, the ends of the jaws 7^a bear upon respective sides of the web 6^b of the track 10 rail 6 when the gibs are pressed into engagement with the lower tie plate 5^b and base flanges 6^a, so that the track rail is held from lateral displacement on the composite tie, and the parts of the latter are moderately 15 clamped together. It will be obvious that by a proper depression of the keys 8, the track rail 6 will be permitted to receive longitudinal adjustment on the cross tie, which will compensate for the expansion and con- 20 traction of the track rails disposed in sequence on the improved cross ties, when affected by changes in temperature. The keys 8 are preferably prevented from vertical displacement by cross pins *c* that are in- 25 serted through transverse perforations in the keys below and near to the lower surface of the cross tie, and it will be apparent that percussion due to traverse of car wheels on the track rails, will settle the keys and main- 30 tain a proper clamping adjustment of the gibs 7.

In Fig. 4, there is shown a pair of fish plates 9, applied upon the opposite sides of the rail web 6^c. Said fish plates that are positioned in the ordinary way at a joint between the ends of two track rails, are as usual held in clamped engagement with the adjacent webs of the track rails by a plurality of bolts *d* and nuts *d'*. For the proper 40 clamping connection together of the plates composing the improved cross tie, gibs 7^c having jaws 7^d on their edges at each end, serve to clamp the base flanges 6^a of the track rails upon the cross tie and the plates 45 of the tie together, when the keys 7^e are forcibly driven into the slots partly occupied by the gibs. The only difference between the gibs 7^c and gibs 7 consists in shortening the upper jaws 7^d so that they will bear upon 50 the fish plates 9, instead of having contact with the webs of the track rails.

In Fig. 5, the form of the fish plates 10 is altered somewhat, permitting their upright members to bear closely upon the webs 6^e of the track rails, and as shown, said fish plates 55 which have intimate contact with the rail webs and base flanges on the track rails, have short studs *g* projected from their upright sides that enter holes formed transversely in 60 the rail webs. The gibs 7^e, that occupy slots in the tie plates indicated in Fig. 5, have jaws 7^h that bear upon the fish plates 10, and it will be seen that keys 7ⁱ, which engage the gibs 7^e, cause the jaws 7^h to bear upon the 65 fish plates 10 with sufficient force to hold the

tie plates assembled and the ends of two track rails alined that are pressed by the fish plates 10. It will also be apparent that by a proper vertical adjustment of the keys that bear on the gibs 7^e, one being shown in Fig. 70 5, the track rails will be properly clamped by the fish plates 10, and the latter will be held so that they can only move a short distance endwise, by the studs *g* that occupy slightly oblong holes in the webs 6^e of adjacent track 75 rails that are arranged in sequence on the improved cross ties. It is claimed that where the gibs are constructed as shown in Fig. 1, their jaws 7^a by impingement upon the webs 6^b of the track rails, afford reliable 80 support for said rails and relieve the strain usually thrown upon the spikes that fasten the rails upon the cross ties.

It will be seen that the manner of securing together the several plates forming a cross 85 tie with gibs and keys, that also secure the track rails on the ties, is a novel and valuable feature, as it virtually dispenses with the necessity of employing bolts for the purpose of holding the track rails on the ties, and at the 90 same time permits the track rails to move endwise sufficiently to compensate for changes in their length. Other points of merit are that the rails cannot become depressed at their ends, that they will be preserved in proper gage, and that the ties will 95 have considerable resilience. It will furthermore be obvious that the keys and gibs holding the rails on the ties, by their removal release the plates of a tie, so that they may be 100 readily removed for repairs of the track and be quickly reassembled when the work has been completed.

The ties are very durable and may in quantity be produced at moderate cost.

Having thus described my invention, I claim as new and desire to secure by Letters Patent:

1. In combination, a cross tie formed of a plurality of resilient metallic plates having different widths and arranged in a tier, said plates having two sets of registering slots therein, a track rail seated upon the tie between the slots of each set, gibs occupying the slots and having jaws on their ends, those at one end of each gib bearing on a base flange of the track rail and those on the other ends of said gibs bearing upon the lower plate of the cross tie, a tapered key forced in each slot and bearing upon the back of a respective gib, and a cross pin occupying a transverse perforation in the lower end of each key adjacent to the cross tie.

2. In combination, a cross-tie formed of a plurality of flat metallic plates that are resilient, the plates differing in width and arranged in a tier, said plates having two spaced sets of slots therein, the slots in each plate registering with corresponding slots in the other plates, a track-rail seated upon the

cross-tie, between the slots forming each set thereof, two fish-plates, each bearing oppositely upon the web and base-flange of the track-rail, two gibbs inserted in respective slots and occupying portions thereof, each gib having two jaws that bear respectively on the base-flanges of the fish-plates and upon the lower side of the cross-tie, tapered keys forced in the remaining portions of the 10 slots, and bearing upon the backs of the gibbs,

and means for securing the keys from vertical displacement.

In testimony whereof I have signed my name to this specification in the presence of two subscribing witnesses.

WILLIAM BOYER.
